UNITED STATES PATENT OFFICE.

FREDERICK W. ANDREW, OF BROOKLYN, NEW YORK, ASSIGNOR TO EISEMANN MAGNETO CORPORATION, OF BROOKLYN, NEW YORK, A CORPORATION OF NEW YORK.

OSCILLATING MAGNETO.

1,416,670.

Specification of Letters Patent. Patented May 23, 1922.

Application filed September 18, 1919, Serial No. 324,543. Renewed April 30, 1920. Serial No. 377,970.

To all whom it may concern:

Be it known that I, FREDERICK WILLIAM ANDREW, a citizen of the United States, and a resident of the city of New York, borough 5 of Brooklyn, county of Kings, and State of New York, have invented certain new and useful Improvements in Oscillating Magnetos, of which the following is a full, clear, and exact specification.

10 My invention relates to electric current generators, more particularly to those used in electric ignition systems employed in connection with internal combustion engines, and consists in devising a novel mechanism 15 for oscillating the movable part of a generator, an example whereof is herein described with reference to the accompanying drawings, wherein—

Fig. 1 is a front elevation of a magneto, 20 provided with the mechanism for oscillating its shaft, constructed according to my invention;

Fig. 2 is a similar view with the oscillator arm, and the nut-cap, removed;

25 Fig. 3 is a longitudinal sectional view on line 3—3, indicated in Fig. 1, looking in the direction indicated by the arrow pointing to the section line;

Fig. 4 is a cross-sectional view on line 30 4—4, indicated in Fig. 3, looking in the direction indicated by the arrow pointing to the section line;

Figs. 5 to 9, illustrate details of construction, Fig. 5 being a side elevation, partly 35 sectional view of one of the spring arms; Fig. 6 a rear elevation of the other spring arm; Fig. 7 a sectional view thereof on line 7—7, indicated in Fig. 6; Fig. 8 a front view, and Fig. 9 a side view of the oscillator arm.

The oscillator mechanism is constructed as follows:

The flanged bushing 11 is keyed or otherwise secured to the magneto shaft 12, the 45 end whereof is screw-threaded correspondingly to the interior screw-thread of the flanged cap-nut 13. The body of the nut 13 is fitted into the bushing 11, which is recessed as shown at 11^a in Fig. 2, and the 50 oscillator arm 14 (see Figs. 8 and 9) is fitted thereon; the central part of the slot 15 being widened correspondingly to the interior annular recess 16 of the bushing 11 to permit passing therethrough of the body of

the cap-nut 13 to be screwed onto the end 55 of the magneto shaft 12. This cap-nut 13 holds in their respective positions the component parts of my improved oscillating mechanism, which are rotatably mounted on the said bushing.

60 The spring arm 17 comprises a perforated plate, shaped as may be seen in Fig. 4, and having a sleeve 18, shown in Fig. 5, preferably made integral therewith, the perforation in the plate and the sleeve 18 65 surrounding it, being interiorly snugly fitted upon the bushing 11. A slot 19 is made in the sleeve 18, into which the inner end of the spring 21 is inserted. At the end of the arm 17 the flange 20 is formed, which 70 though helpful in the operation of the device, is not essential. When the arm 17 is mounted on the bushing 11, the end of the sleeve 18 abuts against the flange 23 of the 75 said bushing, and the said arm is thus rotatable, but not longitudinally movable thereon. The spring 21 is what is technically termed a helical spring, or more commonly called a spring of the clock-spring type. More broadly speaking, I may refer to the 80 spring 21 as one in which the axis of the coils is substantially coincident with the magneto shaft 12 on which the spring is mounted. A spring of this type does not require any housing and is practically free 85 from friction during the operation of the oscillator.

75 The shape of the other spring-arm 24, is shown in Figs. 2 and 6. The perforation 25 in this arm is also snugly fitted upon the 90 bushing 11, and a stud 26 is set in its end for connecting thereto the other outer end of the spring 21. The flange 27 on the end of this arm 24 extends in opposite direction to the flange 20 on the end of the arm 17, 95 whereby both flanges are brought in alignment.

A plate 29 is secured by the nuts 32 to the posts 28, set in the casing 30 of the magneto. On this plate 29 a tongue 31 is 100 formed, extending into the path of the spring arms 17 and 24 and forming a stop arresting the movement of each of the arms when actuated by reaction of the spring 21, as explained further on in the description of 105 the operation of this device.

The oscillator arm 14 is fitted upon the recessed forward end of the bushing 11, (see

Fig. 2) and is secured thereon, and to the magneto shaft 12, by the flanged capnut 13. The oscillator arm 14 is thus rigidly connected with the shaft 12 of the magneto like a crank, so that by swinging it the magneto shaft, and the rotor mounted thereon, are correspondingly actuated. Thereby also, as shown in Fig. 3, the spring-arms 17 and 24, which are rotatably mounted on the bushing 11, are held in their position. The stud 33 is set in the oscillator arm in position to enter into the space between the spring-arms 17 and 24 (see Fig. 2), held open by the stop 31 separating them. This stud 33 is thus in position to engage either one of the arms 17 and 24, according to in which direction the oscillator arm is swung. Each one of the two spring-arms 17 and 24 being connected to one end of the spring 21, and each being prevented by the stop 31 from moving when the other is swung away from the stop, the spring 21 is tensioned by moving the oscillator arm 14 in either direction, and reacts when the force, moving the oscillator arm, ceases to act. By the reaction of the spring, the spring-arm, which was thus swung away from the stop 31, acting upon the stud 33, imparts to the oscillator arm 14, a short but quick impulse in reverse direction. The spring-arm, thus acting on the oscillator arm is stopped by coming in contact with the fixed stop 31, whereas the stud 33 abuts against the other arm, which then acts as a cushion and stop for the oscillator arm. The oscillator arm 14 being rigidly connected with the magneto shaft 12, the latter, and the rotor, or other rotatory part of the magneto, are by the reaction of the spring 21 rapidly swung through an arc, whereby electric current required for the production of the ignition spark, is generated.

The movement of the oscillator arm 14 to effect the tensioning of the spring 21 may be, and preferably is, produced by a cam, or a two or four-pointed star-wheel, mounted on the engine shaft, or upon an intermediate shaft, driven from the engine shaft, in the required position to engage the oscillator arm. The particulars of the construction of these details are determined by the design of the engine, number of cylinders, etc. and as they form no part of my invention, they are not shown in the drawings and not described in detail.

My improved oscillating mechanism may be used on magnetos or other electric current generators, designed to be driven in either direction, the actuating spring being tensioned, and reacting equally, whether the arm 17, connected to its inner, or the arm 24, connected to its outer end, is acted upon. Another advantage resulting from my invention is in that the other spring-arm, the one not acted upon by the oscillator arm 14, acts as a cushion in stopping the swing of

the oscillator arm almost instantly and with a minimum of vibration, in the position, in which it is to be engaged by the next point of rotating star-wheel. This positively prevents a miss of the oscillator arm 14 by the cam, star-wheel, or other device actuating it, so frequently happening in ignition apparatus provided with oscillating mechanism of other construction, and also the jamming of the driving part, cam, star-wheel, etc., with the oscillator arm often occurring when no positive stop is provided, and also avoids jarring of the parts against a non-cushioned stop of the oscillator arm.

A further advantage of my new oscillator resides in the use of a spring which does not require to be confined in a casing. This not only simplifies the construction (and thus reduces the cost of manufacture), but also materially increases the life of the oscillator. It is a well-known fact that the main trouble with oscillators of prior construction is spring breakage. That is particularly true of oscillators using a coiled spiral spring, which must be bent into circular shape and confined in a housing. As the spring contracts and expands, the coils rub against the walls of the housing and are soon worn to a point of breakage. In my invention, this serious difficulty and objection are entirely eliminated.

I claim as my invention:

1. An oscillating mechanism for a magneto or other electric current generator, the mechanism comprising a coiled spring and two arms rotatably mounted on the magneto shaft, each of said arms being connected to one end of said spring, an arm rigidly secured to the magneto shaft, means on said last-mentioned arm for moving either of said two arms, and a fixed stop in the path of said two arms for limiting the movement of each in one direction.

2. An oscillating mechanism for a magneto or other electric current generator, the mechanism comprising a sleeve rotatably mounted on the magneto shaft, an arm integral with said sleeve, a coiled spring having its inner end connected to said sleeve, a second arm also rotatably mounted on the magneto shaft and connected to the other end of said spring, a fixed stop for limiting the movement of each of said two arms in one direction, an arm rigidly secured to the magneto shaft, and means on said last-mentioned arm for engaging either of the arms connected to the ends of said spring.

3. An oscillating mechanism for a magneto or other electric current generator, the mechanism comprising a coiled spring, two arms rotatably mounted on the magneto shaft, each of said arms being connected to one end of said spring, a fixed stop for limiting the movement of each arm in one direction, an arm rigidly secured to the mag-

neto shaft and adapted to be intermittently actuated, and means on said last-mentioned arm adapted to engage either of the two arms connected to the ends of said spring.

5. An oscillating mechanism for a magneto or other electric current generator, the mechanism comprising a pair of members rotatably mounted on the magneto shaft, spring means connected to said members and 10 adapted normally to urge them toward each other, means for limiting the movement of said members under the action of said spring means, and an intermittently operable arm fixed on the magneto shaft for engaging 15 either of said members and actuating the same against the tension of said spring means, whereby the actuated member will under the action of said spring means impart an accelerated return movement to said 20 arm.

5. An oscillating mechanism for a magneto or other electric current generator, the mechanism comprising a pair of oscillating members mounted on the magneto shaft, a 25 coiled spring also mounted on the magneto shaft and connected at its ends to said members, said spring being so constructed and arranged that the axis of the coils is substantially coincident with the axis of said 30 shaft, an arm operatively connected with the magneto shaft and adapted to move either member from its normal position against the tension of said spring, whereby the actuated member will impart an accelerated 35 return movement to said arm under the action of the tensioned spring, and means for holding either member against movement during the operation of the other member.

6. An oscillating mechanism for a magneto or other electric current generator, the mechanism comprising an intermittently operable arm rigidly secured to the magneto shaft, a pair of rotatable members having hub portions for mounting said members on the magneto shaft, said members being arranged to engage said arm on opposite sides thereof, a helical spring for rocking said members independently of each other in opposite directions, whereby the operation of said arm in either direction moves one of said members against the tension of said helical spring, so that the release of said arm permits the spring-pressed member to move the arm quickly back to normal position, and means for holding either member against movement during the operation of the other member.

7. An oscillating mechanism for a mag-

neto or other electric current generator, the mechanism comprising a helical spring and 60 two independently rotatable arms, means on said arms for mounting them on the magneto shaft, each of said arms being connected to one end of said spring, means for actuating either arm against the action of 65 said helical spring, and means for holding either arm against movement during the operation of the other arm.

8. An oscillating mechanism for a magneto or other electric current generator, the 70 mechanism comprising a helical spring and two independently rotatable arms mounted on the magneto shaft, each of said arms being connected to one end of said spring, means for actuating either arm against the 75 action of said helical spring, each of said arms being arranged to act as a yieldable stop for said actuating means and the returning arm, and means for holding either arm against movement during the operation 80 of the other arm.

9. An oscillating mechanism for a magneto or other electric current generator, the mechanism comprising a coiled spring 85 mounted on the magneto shaft, said spring being so constructed and arranged that the axis of the coils is substantially coincident with the axis of said shaft, an intermittently operable arm rigidly connected to the magneto shaft and yieldably held in normal position by said spring, and means whereby the actuation of said arm in either direction from normal position places said spring under tension, so that the release of said arm causes said spring to return the arm to 95 normal position.

10. An oscillating mechanism for a magneto or other electric current generator, the mechanism comprising a pair of rotatable members having hub portions for mounting 100 said members on the magneto shaft, a coiled spring also mounted on the magneto shaft, said spring being so constructed and arranged that the axis of the coils is substantially coincident with the axis of said shaft, 105 means on each of said members for engaging one end of said spring, an arm for actuating said members, and stop means for holding either end of said spring stationary during the operation of said arm in either 110 direction to place said spring under tension.

FREDERICK W. ANDREW.
